UNITED STATES PATENT OFFICE.

WILLIAM P. BETTENDORF, OF DAVENPORT, IOWA; J. W. BETTENDORF ADMINISTRATOR
OF SAID WILLIAM P. BETTENDORF, DECEASED.

DRAFT-RIGGING AND SUPPORT THEREFOR.

1,072,300.

Specification of Letters Patent.

Patented Sept. 2, 1913.

Application filed June 6, 1908. Serial No. 437,193.

To all whom it may concern:

Be it known that I, WILLIAM P. BETTENDORF, a citizen of the United States, and a resident of Davenport, in the county of Scott and State of Iowa, have invented certain new and useful Improvements in Draft-Rigging and Support Therefor, of which the following is a full, clear, and exact description.

10 My invention relates to draft-rigging for cars and the support therefor, which are particularly applicable to cars the underframes of which employ a single rolled metal beam center-sill.

15 The object of my invention is to provide a draft-rigging which can be inserted and retained in a suitable longitudinal opening in the ends of the single rolled metal beam constituting the center-sill, which will 20 impart the pulling strain of the car-coupler, to the center-sill through the medium of devices that reinforce the end portions of the center-sill, and prevent the spreading of the 25 divisions or bifurcations thereof, substantially as hereinafter fully described, and as particularly pointed out in the claims.

In the drawings:—Figure 1 is a longitudinal section of the end portion of an under-frame for cars having my improvements applied thereto. Fig. 2 is a transverse section taken on dotted line 2, 2, Fig. 1. Fig. 3 is a horizontal section of a fragment of said draft rigging, including the rear end portion of the draw-bar of the car-coupler.

Referring to the drawings A represents a single center-sill, consisting, preferably, of an I-beam having a portion of its web cut away longitudinally, a distance extending 40 from the ends thereof (which are attached in suitable manner to the end-sill B) to a point corresponding to the rear end of the housing in which the springs of the draft-rigging are seated, substantially as herein- 45 after fully explained. Removing the ends of the web of the center-sill in this manner leaves an upper bifurcation α whose forward extremity is connected to the end-sill B by means of suitable castings α^2 , and a lower 50 bifurcation α' whose forward end rests and is secured upon a ledge b , made by flanging the central portion of the lower horizontal part of the rectangular cast metal frame C, which is provided with an opening below the 55 plane of the center-sill back through which

the draw-bar D of the car-coupler extends. The draw-bar of the coupler extends longitudinally into the space or guide-way made by cutting away this web, which guide-way is increased in height commencing at a point 60 adjacent to the rear end of the draw-bar and extending throughout the remainder of its length to its end farthest from the end-sill. The web of the center-sill, at the rear end of this guide-way is reinforced on each side 65 by plates E, the construction of which is substantially the same as the corresponding plates of the draft rigging described and claimed in an application for Letters Patent of the United States, filed by me May 23, 70 1908, and numbered 434,669, and the longitudinal edges of this guide-way are reinforced by a substantially U-shaped binding strip d of angle-iron, the ends of which terminate about midway the length of the narrower portion of the guide-way, and the bend of which extends around the back of the rear semi-circular end of plates E. This binding-strip d is so arranged and riveted to the web of the center-sill that the horizontal 75 flange thereof projects laterally in the plane of the edges of said guide-way and provides a broad surface which assists in supporting and guiding the movement of the parts of the draft-rigging, as will herein- 80 after be more fully described. The rear part of the guide-way is occupied by a housing 2, which contains the springs 3, and consists of a tubular casing, which, preferably, is square in cross-section, and has its rear 85 closed end, 4, bear against the forward edges of reinforcing plates E, and has its forward end open. This housing is retained in position by brackets 5, which latter are secured by rivets or bolts to the vertical portion of the angle-iron binding-strips d , below the guide-way K, and their upturned ends confine and prevent the lateral 90 displacement of the housing. The length of housing 2 is less than that of the wider rear 95 portion, K, of the guide-way, and in the space between its forward end and the shoulders at the forward end of said wider portion, K, a buffering-block 6 is placed that consists of a substantially rectangular casting of 100 sufficient thickness, and is kept normally in engagement with the rear end of the draw-bar D, by the pressure of springs 3, through the medium of a suitable follower-plate 7' and eccentrically journaled cam-blocks 8 and 110

9, journaled and operating within the forward portion of the housing, substantially as shown in Fig. 3 of the drawings. The follower-plate, 7, fits and slides in the bore of the housing and is directly engaged by the springs, and the cam-blocks are located between said follower-plate and buffering-plate.

The buffering-plate is provided with laterally projecting upper and lower lugs 10, 10, on each side, that normally bear forward against the vertical portion of a rectangular frame or yoke 12, which latter surrounds the buffering-block, and consists of two substantially corresponding sections, the upper and lower ends of each of which are bent inward and, preferably, conform to the shape of and are secured by rivets or otherwise to the upper and lower flanges of the center-sill. The inner edges of these yoke-sections are flanged to increase the engaging surfaces thereof bearing against the center-sill and the buffering-block, and it is through these flanges that the rivets or bolts are passed.

A short distance from its rear end, the sides of the draw-bar are, preferably, built out or provided with bosses and said rear end is also provided with a transverse opening, which, preferably, passes through said bosses and forms a seat for a transverse bar or key 13, whose ends project beyond the sides of the draw-bar a suitable distance. The vertical sides of the housing are, preferably, in the same vertical plane as the outer surfaces of the bosses just referred to, and said housing, at about its center of length and in the same horizontal plane as the key 13, is provided with laterally projecting trunnions, 14, which latter are connected by links 15 with the projecting ends of the key 13. Openings 16 in the forward ends of the links (through which the ends of the key pass) are elongated longitudinally to permit the links to have a slight forward movement, or, the draw-bar to have a slight rearward movement independent of the links and the bodies of said links pass between the lug 10 of the buffering-block and their rear ends are immovably connected to and move with the housing at all times.

In operation, when a pushing motion is imparted to the car-coupler, it moves to the rear independently of the links 15, for a short distance, and, through the buffering-block and rolling cam-members 8 and 9, slightly compresses the springs 3, which latter neutralizes the shock and imparts the strain through the rear end of the guide-way to the center-sill, until the ends of the key come in contact with the rear end of the openings 16 of the links 14, whereupon the buffering strain is imparted direct to the housing of the spring and through it direct to said center-sill. When the draw-bar is sub-

jected to a pulling strain, key 13, through the medium of links 15, draws the housing forward and compresses the springs, 3, against the follower-plate, the cam-members 8 and 9, the buffering-block 6 and the rectangular yoke or frame 12, until the limit of the forward compression of the springs is reached, or until said springs compress sufficiently to resist the pulling strain. The rectangular yoke or frame 12 not only constitutes the medium through which the pulling strain of the coupler is imparted to the center-sill, but it also combines and ties the upper and lower bifurcations of the ends of the center-sill together, and gives greater rigidity and strength to the ends of the sill where most needed.

What I claim as new is:—

1. In a car the combination with end-sills and a single metal beam center-sill, the ends of which are connected to said end-sills, and which has a portion of its web between its edges cut away to form a continuous space or guide-way extending from its ends to a point beyond the rear ends of the springs, a draw-bar extending longitudinally into said guide-way, springs actuated by said draw-bar, means secured to said center-sill for retaining said draw-bar in place within said guide-way and devices including said springs for transmitting the strain of the pull of said draw-bar to the center-sill.

2. In a car the combination with end-sills and a single metal beam center-sill, the ends of which are connected to said end-sills, and which has a portion of its web between its edges cut away to form a continuous space or guide-way extending from its ends to a point beyond the rear ends of the springs, a draw-bar extending longitudinally into said guide-way, springs actuated by said draw-bar, means for retaining said draw-bar in place within said guide-way and follower abutment means connecting the upper and lower bifurcations of said sill for transmitting the strain of the pull of the draw-bar to the center-sill.

3. In a car the combination with end-sills and a single metal beam center-sill, the ends of which are connected to said end-sills, and which has a portion of its web between its edges cut away to form a continuous space or guide-way extending from its ends to a point beyond the rear ends of the springs, a draw-bar extending longitudinally into said guide-way, springs co-operating with said draw-bar, means for retaining said draw-bar in place within said guide-way and a frame surrounding said center-sill and connecting the upper and lower bifurcations thereof for transmitting the pull of the draw-bar to the center-sill.

4. In a car the combination with end-sills, and a single metal beam center-sill the ends

of which are connected to said end-sills and which has a portion of its web between its edges cut away to form a continuous space or guide-way extending from its ends to a point beyond the rear ends of the springs, of a draw-bar extending into said guide-way, a buffer-block engaging the draw-bar having laterally projecting lugs, springs for pressing said buffer-block forward, and means for retaining said draw-bar in place in said guide-way and means engaged by the lugs of said buffer-block for transmitting the pull of the draw-bar to the center-sill.

5. In a car the combination with end-sills, and a single metal beam center-sill the ends of which are connected to said end-sills and which has a portion of its web between its edges cut away to form a continuous space or guide-way extending from its ends to a point beyond the rear ends of the springs the edges of which guideway are provided with lateral flanges, of a draw-bar extending into said guide-way, a buffer-block engaging the draw-bar, having laterally projecting lugs, 25 springs for pressing said buffer-block forward, and means for retaining said draw-bar in place in said guide-way and means engaged by the lugs of said buffer-block for transmitting the strain of the pull of the draw-bar to the center-sill.

6. In a car the combination with end-sills, and a single metal beam center-sill the ends of which are connected to said end-sills and which has a portion of its web between its edges cut away to form a continuous space or guide-way extending from its ends to a point beyond the rear ends of the springs, of a draw-bar extending into said guide-way, a buffer-block engaging the draw-bar having laterally projecting lugs, springs for pressing said buffer-block forward, a suitable housing for said springs, and means for retaining said draw-bar in place in said guide-way, and means engaged by the lugs of said

45 buffer-block for transmitting the strain of the pull of the draw-bar to the center-sill.

7. In a car the combination with end-sills and a single metal beam center-sill the ends of which are connected to said end-sills and

which has a portion of its web between its edges cut away to form a continuous space or guide-way extending from its ends to a point beyond the rear ends of the springs, of a draw-bar extending into said guide-way, a buffer-block engaging the draw-bar having laterally projecting lugs, springs for pressing said buffer-block forward, and means for retaining said draw-bar in place in said guide-way, and distinct means engaged by the lugs of said buffer-block for transmitting the strain of the pull of the draw-bar to the center-sill.

8. In a car the combination with end-sills, and a single metal beam center-sill the ends of which are connected to said end-sills and which has a portion of its web between its edges cut away to form a continuous space or guide-way extending from its ends to a point beyond the rear ends of the springs, of a draw-bar extending into said guide-way, a buffer-block engaging the draw-bar, having laterally projecting lugs, springs for pressing said buffer-block forward, and means for retaining said draw-bar in place in said guide-way, and a frame surrounding said center-sill and connecting the upper and lower bifurcations and engaged by the lugs of said buffer-block for transmitting the strain of the pull of the draw-bar to the center-sill.

9. A draft rigging for cars comprising a single center-sill having a continuous longitudinal transverse opening extending from its ends past the location of the springs, a draw-bar retained within said openings, devices including said springs for cushioning the same, and a member adjacent to the end of said draw-bar and exterior to the thrust of the same for connecting the bifurcations of said opening.

In testimony whereof I have hereunto set my hand and seal this 7th day of April, A. D., 1908.
